UNITED STATES PATENT OFFICE.

RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

EYELETING-MACHINE.

1,156,936.

Specification of Letters Patent. Patented Oct. 19, 1915.

Application filed November 2, 1910. Serial No. 590,272.

To all whom it may concern:

Be it known that I, RALPH C. SIMMONS, a citizen of the United States, residing at Beverly, in the county of Essex and State of Massachusetts, have invented certain Improvements in Eyeletting-Machines, of which the following description, in connection with the accompanying drawings, is a specification, like reference characters on the drawings indicating like parts in the several figures.

This invention relates to machines for setting eyelets or other fasteners and one of its objects is to improve the feeding or spacing mechanism and render possible certain novel operations in eyeletting machines.

The invention is herein illustrated as embodied in a machine of the type disclosed in United States Letters Patent No. 683,488, granted October 1, 1901, to M. H. Pearson, although the invention is not limited to machines of this particular type, nor to eyeletting machines, but may be embodied advantageously in machines for setting lacing hooks, studs or similar articles.

More particularly, it is an object of the invention to provide feeding mechanism for an eyelet setting machine which shall have a wide range of adjustment so that eyelets of large diameter may be set with a very wide spacing and small eyelets may be set by the same machine with short or close spacing.

A sufficiently wide spacing for large eyelets is attained with difficulty by the employment of feeding mechanism of the type disclosed in said patent above identified. In that construction the feeding movement of the work-engaging devices is limited by their connection with a pivoted controlling link. One method by which the range of this movement may be increased in accordance with the present invention is by substituting for the pivoted controlling link, means for guiding one part of the feed transmitting mechanism in a substantially rectilinear path and providing mechanism for changing the position of said guiding means, whereby a greater or lesser resultant feeding movement is imparted to said work-engaging devices. Such construction will permit a wide feeding movement, when de-

sired, because substantially the entire movement of the feed transmitting mechanism may be guided in the direction of the feed, no motion being wasted.

Another important feature of the invention consists in the provision of automatically operating means for regulating the extent of the feeding movement in order that the eyelets or other fasteners may be set automatically with varying spacing.

It is, in some cases, desired to set the lowest eyelets with one spacing and the upper eyelets with a greater spacing, or to increase progressively the spacing of the eyelets from the instep toward the top of the quarters. One method of effecting these results, in accordance with the present invention, consists in providing an adjustable lever for controlling the extent of the feeding movement and an intermittently acting cam or other device for regulating the position of said controlling lever. Preferably the regulating cam may be actuated by the movement of the feeding devices and the desired operation may be attained by selecting a cam of suitable contour.

Other features of the invention, relating particularly to the construction of the automatic feed regulating mechanism, consist in the provision of means for preventing the over-running of the regulating cam, and in providing a novel mounting for the regulating cam whereby it may be readily removed to permit the substitution of another of different contour.

These and other features of the invention will be best understood and appreciated from the following description of a preferred embodiment thereof, selected for purposes of illustration, in connection with the accompanying drawings, in which,—

Figure 1 is a plan view of portions of a duplex eyeletting machine showing my invention as embodied therein; Fig. 2 is a similar view showing the feeding mechanism adjusted for wide spacing; Fig. 3 is a fragmentary side elevation of the machine shown in Fig. 1; and Fig. 4 is a detail view in perspective showing the mounting for the feed regulating cam.

Before proceeding to a detailed description of the various parts of the machine

which comprise more particularly the subject-matter of this invention, it will be convenient to refer to the principal operative parts and their general mode of operation 5 and relative arrangement. The machine illustrated in the drawings has a frame 2 which is provided with bearings for the main shaft 4 adapted to be connected at one end, through a suitable driving clutch, with 10 any convenient source of power and having a hand wheel 6 on the other end. The present machine, like that of said patent, comprises oppositely disposed punches 8 and oppositely disposed setting dies 10 arranged 15 in bearings in a support or feed frame 12, with an anvil or die plate 14 also mounted in said feed frame, arranged between the oppositely disposed punches and setting dies. A guide plate 16 is mounted in the 20 frame 2 and extends adjacent to the anvil 14 when the latter is in its initial position. Oppositely disposed spring presser feet are arranged to bear upon the sides of the guide plate 16 and serve to hold and guide the 25 work properly as it is fed into punching and setting positions and edge gages 18 are also mounted on the guide plate.

In presenting work to the machine the two quarters of an upper are inserted between the opposite sides of the guide plate 30 16 and the respective presser feet with their edges against the edge gages 18. The machine is then set in operation whereupon the punches are actuated to punch a hole in each 35 quarter, then the feed frame 12 is moved rearwardly to bring the setting dies into alignment with the previously punched holes, and the eyelet raceways 20 are advanced presenting eyelets to the setting dies 40 as the latter are actuated to set a pair of eyelets simultaneously in the two quarters. After the setting dies have set the eyelets, they are released slightly but still held in engagement with the work, and then the 45 feed frame 12 is moved to the left to feed the work a distance depending upon the spacing required between successive eyelets. The feed frame then makes its return movement, bringing the punches back to 50 their initial position, and the operations are repeated.

A detailed description will now be given of the mechanism for carrying out the operations above outlined, including the novel 55 mechanism and arrangement of parts for effecting and regulating the feeding of the work which constitute the subject-matter of the present invention. The feed frame 12 is pivotally connected by the spindle 24 at 60 its rear end to the transverse arms of a forked bell crank lever 22. The bell crank lever 22 is fulcrumed on the frame by means of a pin 26 and carries a roller 28 running in a cam 30 on the shaft 4. The cam 30 is 65 timed to shift the feed frame rearwardly

after the punching operation to bring the setting dies 10 into line with the holes previously formed by the punches 8, and forwardly during the return movement of the feed frame to bring it into its initial position. 70

The lateral movement of the feed frame, which results in the feeding movement of the work, is effected by the cam 32 on the main shaft acting through the lever 34 and the transmitting links 36 and 38, the latter of which is pivotally connected to the feed frame and acts to swing the frame about the spindle 24 as an axis. The throw of the cam 32, and the oscillation of the lever 34, is constant and accordingly the extent of feeding movement imparted to the frame 12 would be constant if there were a direct connection between the lever 34 and the frame 12. In accordance with the present 80 invention, however, it is proposed to resolve the lateral movement of the forward end of the lever 34 into components acting laterally and longitudinally and to transmit only the laterally acting component to the feed frame 12. By regulating the ratio of the two component movements the extent of the feeding movement and the distance between successive eyelets may be controlled. To this end, a roller 40 is mounted at or 85 near the point of connection of the transmitting links 36 and 38 and disposed in operative relation therewith is a lever 42 having a straight guideway formed therein. The lever 42 is mounted on a short shaft 100 43, being movable over a segment plate 44 and may be maintained in any desired adjusted position by stop pins inserted in holes in the plate. It will be apparent that when the lever is turned so that the guideway extends substantially at right angles to the lever 34 practically all of its lateral movement will be transmitted through the links 36 and 38 to the feed frame. On the other hand, as the lever is swung carrying 105 the guideway toward parallelism with the lever 34, more and more of the lateral movement of the lever is taken up by movement of the roller 40 longitudinally and the effective lateral movement becomes less and less, thus decreasing the extent of the feeding movements of the feed frame 12. 110

Ordinarily the lever 42 is moved into position to give the desired spacing and maintained in such position during the eyeleting operation, being adjusted only for different sizes or styles of shoes. It is, in some cases, desirable to set successive eyelets with varying spacing, for example, to increase the spacing progressively from the lowest to 115 the uppermost eyelet. One manner of accomplishing this result consists in slightly moving the spacing lever 42 between each successive setting operation so that each feeding movement of the frame 12 shall be 120 125

greater than the one before. To this end the spacing lever 42 is provided with an arm 50 carrying a cam roller on its under side which projects into the path of a suitably shaped edge cam 52 mounted below the segment plate 44 on a spindle 53. A tension spring 54 extending between the under side of the arm 50 and a stationary arm 56 serves to maintain the cam roller in contact with the periphery of the cam 52. The cam is actuated by a pawl and ratchet mechanism comprising a ratchet wheel 58 fast with the cam 52 and a pawl 60 yieldingly mounted in a carrying member 62 pivoted in the spindle 53. The pivoted carrier 62 is oscillated by the transverse movement of the feed frame 12 through the lever 64 and the two connecting links 66 and 68, the latter of which is pivoted to the forward end of the feed frame. The oscillation of the carrier 62 may be adjusted by shifting the point of connection of the link 66 with the lever 64.

It has been found that the rapid rotary movement imparted to the cam 52 during an oscillation of the carrier 62 tends to make the cam move more than the desired distance or overrun, and it is desirable, therefore, to provide means for stopping the turning movement of the cam after it has made its predetermined angular movement. One convenient manner of effecting this result consists in providing means for positively forcing the pawl 60 against the ratchet wheel 58 at the end of its driving stroke so that relative movement of the ratchet wheel and pawl is prevented. To this end the pawl is provided with a contact piece 70 and arranged in the path thereof is a stop screw 74 projecting inwardly from a lug downwardly extending from a stationary arm 72. When it is desired to operate the machine for uniform spacing, without the automatic regulating mechanism, the pawl 58 may be withdrawn against the compression of its spring and maintained inoperative by giving the contact piece 70 a quarter turn. In this position the contact piece will oscillate in a path below the stop screw 74.

In the drawings the cam 52 is illustrated as having thirteen steps at progressively increasing radial distances from the spindle 53 and the ratchet wheel 58 is provided with thirteen corresponding teeth. The machine will, therefore, set thirteen eyelets at progressively increasing distances, an arrangement which is frequently desired in eyeleting women's boots.

In order that the cam 52 may be readily removed to permit the substitution of other cams having different contours the spindle 53 is provided with a pair of spring retaining arms 55 which normally expand and engage the hub of the ratchet wheel 58. The cam 52 is mounted upon the hub of the ratchet wheel and retained thereon by a nut,

as clearly shown in Fig. 4. By merely pressing the arms 55 together the cam and ratchet wheel may be slipped off and others substituted. Instead of employing a cam with thirteen equal steps, it will be obvious that cams of various contours may be employed, for example, one having a contour shaped to increase the spacing while the first few eyelets are set and then to decrease the spacing of the remaining eyelets, or one having a contour shaped to maintain the spacing of the first eyelets uniform and then increase the spacing of the remaining eyelets.

The elements of the eyeleting machine not already described may be of any suitable or well known character, for example, similar to the construction disclosed in United States Letters Patent No. 934,066, granted to G. Goddu September 14, 1909. As illustrated in the accompanying drawings, the levers 80 are arranged to actuate the punches 8 and the setting dies 10 according to the position of the feed frame, the punches 8 being shown in operative position in Fig. 3, and spring actuated levers 81 are provided for retracting the punches and sets from the work. The raceways 20 are mounted in a pivoted bracket 82 and are swung toward the right into delivering position and then in the opposite direction by the cam 83 acting through the lever 84 and an interposed link.

Having now described my invention, what I claim as new and desire to secure by Letters Patent of the United States is:—

1. A machine of the class described having, in combination, a supporting frame, work-engaging means mounted therein, means for moving said frame to feed the work, said means including a transversely oscillating lever and pivoted transmitting links, and feed regulating means comprising an angularly adjustable guideway for controlling the direction of movement of said transmitting links.

2. A machine of the class described having, in combination, a supporting frame, work-engaging means mounted therein, means for moving said frame to feed the work, said means including a transversely oscillating lever and pivoted transmitting links, feed regulating means comprising a guideway, a co-operating roller mounted at the point of connection of said links, and means for adjusting said guideway.

3. A machine of the class described having, in combination, work-engaging devices, a supporting frame therefor, a link pivoted thereto and having one end guided in a rectilinear path, means acting through said link to move the frame for feeding the work, and means for changing the direction of movement of the guided end of said link to regulate the extent of feeding movement.

4. A machine of the class described hav-

ing, in combination, punching devices, oscillatory work-feeding means, and means actuated by said work-feeding means in its feeding movement for varying the extent of 5 the feeding movement.

5. A machine of the class described having, in combination, setting devices, a carrier therefor movable in feeding the work, and means actuated by the carrier in its 10 feeding movement for regulating the extent of the feeding movement.

6. A machine of the class described having, in combination, setting devices, a carrier therefor, means for moving said carrier 15 to feed the work, a cam for regulating the extent of said feeding movement, and a lever connected with the carrier and actuated during its feeding movement for advancing said cam.

20 7. A machine of the class described having, in combination, punching and setting devices, a carrier in which one of said devices is mounted arranged for moving said device while in engagement with the work 25 to feed the work, and means actuated by the feeding movement of said carrier for regulating the extent of its feeding movement.

8. An eyeleting machine having, in combination, a work-engaging device, a carrier 30 in which said device is mounted arranged for moving said device to feed the work, and means actuated by the feeding movement thereof for regulating the extent of its feeding movement.

35 9. An eyeleting machine having, in combination, a work-engaging device, means for moving said device to feed the work, a movable guideway for controlling the extent of its feeding movement, and means for automatically changing the direction in which 40 the guideway extends to vary the extent of the feed.

10. An eyeleting machine having, in combination, a work-engaging device, a cam and 45 connecting mechanism for moving said device to feed the work, a lever for controlling the extent of its feeding movement, and means actuated automatically and simultaneously with the feeding movement of 50 said device for swinging said lever to vary the extent of the feed.

11. A machine of the class described, having, in combination, a feed frame, setting devices carried thereby, means for swinging 55 said frame while the setting devices are in engagement with the work to feed the work, a ratchet mechanism connected with said feed frame, and means actuated by said ratchet

mechanism to vary the extent of the swinging movement of said frame.

60

12. An eyeleting machine having, in combination, work-engaging devices, a lever arranged to oscillate uniformly for moving said devices to feed the work, and automatically controlled mechanism interposed 65 between said work-engaging devices and said uniformly oscillated lever for regulating the extent of the feeding movement.

13. A machine of the class described having controlling mechanism for work feeding 70 means, including a cam and connections, said cam having a contractible spindle permitting ready removal thereof.

14. A machine of the class described having, in combination, a movable work feeding 75 member, actuating means therefor, transmission devices interposed between the feeding member and its actuating means, and a guideway arranged to control the movement of the transmission devices arranged for 80 angular adjustment to vary the effect of the transmission devices upon the feeding member.

15. A machine for setting eyelets having, in combination, a work-engaging device, a 85 carrier in which said device is mounted arranged for intermittently moving said device to feed the work, and means actuated by the feeding movement thereof for progressively increasing the extent of the feed- 90 ing movement.

16. A machine for setting eyelets having, in combination, a work-engaging device, a carrier in which said device is mounted arranged for moving said device to feed the 95 work, and means actuated by the feeding movement thereof for increasing the extent of the feeding movement between two successive eyelets.

17. A machine of the class described having, in combination, a work engaging device, a carrier therefor, means for moving the carrier to feed the work, a cam for regulating the extent of the feeding movement of the carrier, and means connected with 105 said carrier and actuated by its feeding movement for changing the position of the cam.

In testimony whereof I have signed my name to this specification in the presence of 110 two subscribing witnesses.

RALPH C. SIMMONS.
